CLAIM

The ornamental design for a display screen with a graphic user interface, as shown and described.

DESCRIPTION

The patent or application file contains at least one drawing executed in color. Copies of this patent or patent application publication with color drawings will be provided by the Office upon request and payment of the necessary fee.

The FIGURE is a front view of a display screen with a graphical user interface.

The broken lines shown in the FIGURE including portions of the display screen and portions of graphic user interface are for the purpose of illustrating portions of the article and form no part of the claimed design.

1 Claim, 1 Drawing Sheet
